CLAIM

The ornamental design for a mechanical connector for band, as shown and described.

DESCRIPTION

FIG. 1 is a front perspective view of a mechanical connector for band showing our new design;

FIG. 2 is a rear perspective view thereof;

FIG. 3 is a bottom view thereof;

FIG. 4 is a top view thereof;

FIG. 5 is a left side view thereof;

FIG. 6 is a right side view thereof;

FIG. 7 is a rear view thereof; and,

FIG. 8 is a front view thereof.

The broken lines in the drawings represent portions of the mechanical connector for band and form no part of the claimed design.

1 Claim, 4 Drawing Sheets
